US0D1016519S

(12) **United States Design Patent** (10) Patent No.: **US D1,016,519 S**
(45) Date of Patent: ** Mar. 5, 2024

(54) **TOWEL RACK**

(71) Applicant: **Juan Chen**, Fuzhou (CN)

(72) Inventor: **Juan Chen**, Fuzhou (CN)

(**) Term: **15 Years**

(21) Appl. No.: **35/516,423**

(22) Filed: **Feb. 8, 2023**

(80) **Hague Agreement Data**

Int. Filing Date: **Feb. 8, 2023**

Int. Reg. No.: **DM/226726**

Int. Reg. Date: **Feb. 8, 2023**

Int. Reg. Pub. Date: **Feb. 24, 2023**

(51) LOC (14) Cl. **06-04**

(52) U.S. Cl.

USPC **D6/548**; D6/549

(58) **Field of Classification Search**

USPC D6/518-520, 522-524, 546-549, 553, D6/566
